THOMAS ROBINSON, OF NEW YORK, N. Y., ASSIGNOR TO LANCASTER ASPHALT, INC.,
OF NEW YORK, N. Y., A CORPORATION OF DELAWARE

PREPARED BUILDING PRODUCT

Application filed June 19, 1928. Serial No. 286,502.

This invention relates to building products capable of withstanding exposure to the elements and forming a water-proof surface, such that these products may be employed for 5 roofing, siding, and other similar purposes. More particularly, the invention is concerned with a new product which is to a large extent made up of a mastic, which is more or less fluent when heated and hardens on cooling, this mastic giving the element the desired body and strength. The invention further comprehends a process and apparatus by which this product may be produced rapidly, at low cost, and with a high percentage 10 of the output of first quality. The new product may be made in various shapes and forms for different uses, but as it is of particular utility and affords important advantages for roofing purposes, an adaptation of the invention for that purpose will be described by way of illustration.

Prepared roofing now widely used in place of slate, wood, shingles and the like, has numerous advantages and some disadvantages. 25 It is cheaper than wood shingles, more resistant to fire and of at least equal durability, but one of the usual components of such roofing is rag felt which is relatively expensive. This felt forms the basis of the material and 30 it is customarily saturated and coated with bituminous substances such as asphalt and then given a wear surface of crushed slate, etc. As the felt, even in the heaviest and most expensive grades is relatively thin, a 35 roofing element with a felt base is likewise thin and the exposed butt does not cast any considerable shadow so that the appearance of a roof laid with these elements is less attractive than that of a wood shingle or tile 40 roof. Furthermore, the felt which represents the greatest item of expense in the manufacture of this roofing is itself the least durable part and in the course of time, the felt deteriorates and rots due to exposure to the 45 weather, the edges of the elements warp and curl making them unsightly and sometimes causing leaks, and in the course of time, the felt disintegrates.

The present invention is accordingly directed to the provision of a novel roofing ma-

terial which may be made at lower cost than prepared roofing employing felt as the foundation member or base, and which has a longer life than the ordinary prepared roofing. This material can be readily produced in different shapes and sizes and in particular, in the form of thick-butt shingles. The new product represents a departure from hitherto accepted practice in that, while felt or similar material is used, it is not employed 55 as the base or body, but that base is a hardened mastic of the desired shape preferably wholly enclosed in a jacket of thin sheet material which may be felt of a weight much less than that used in ordinary commercial 60 roofing.

The mastic I prefer to use to form the core or base of the new product is a mixture in suitable proportions of a bituminous compound such as asphalt, and granular material 70 or grit, such as crushed rock, crushed slate, sand and other similar substances. In some instances, it may be desirable to use infusorial earth, asbestos sand, fibrous asbestos and the like in addition to or in place of the 75 granular material, to produce articles of different weights and other characteristics, and these ingredients are satisfactory for such special purposes. This mastic core is enclosed wholly or in part by fibrous sheets, preferably 80 rag felt, which is not saturated except as an incident to other operations. These sheets form a jacket for the core, adding to its strength and durability, defining its shape and carrying the gritty wear material af- 85 fixed thereto by a suitable adhesive such as an asphalt coating.

The new material is produced by a process which involves drawing a web of unsaturated felt from a supply, and applying to one surface a coating of asphalt or the like. In the ordinary roofing process, such felt is saturated with a low melt point asphalt before any other operation is performed on it, and after this, the felt is cooled and a coating of 90 asphalt of a higher melt point than the saturant in which the wear surface is to be embedded is applied. In the new process, however, the unsaturated felt receives the 95 coating of asphalt at once, then the wear sur- 100

face is applied, and this coating material is put on in a condition such that it enters into the pores of the felt to a substantial distance. The felt used is relatively very thin so that this seeping in the coating may readily extend partly through the felt without difficulty.

After the coating operation, a layer of mastic in more or less fluent condition is applied to the desired thickness on the face of the felt opposite to that coated. This layer of mastic is of substantial thickness but is applied in such condition that the asphaltic component may enter into the felt. By properly controlling the application of coating and mastic and the fluidity thereof, it is possible to insure that the coating compound and the plastic ingredient of the mastic, which are the same and preferably asphalt of the same melting point will extend entirely through the felt and unite to produce complete saturation. After the sheet has received its mastic facing, it is cooled so that the mastic receives an initial set. Then a pair of such sheets are placed together with their mastic coatings between, and shaping and cutting operations are performed to unite the sheets into a single element of the desired form and size. In the finished product, the mastic forms the base, and upon each face is a layer of felted fibres. Through this layer extends the asphaltic compound in a substantially continuous mass from the core to the outer layer carrying the wear surface. The felted sheets forming the jacket are thus fully impregnated and saturated and this result is obtained without performing a separate operation for the purpose.

The product, process and apparatus of the present invention include many features of novelty in addition to those briefly referred to, which will be more apparent upon consideration of the accompanying drawings and detailed description that follows. In these drawings:

Figs. 1A and 1B together illustrate somewhat conventionally the layout in side elevation of the apparatus for producing the new elements;

Fig. 2 is a view in side elevation of modified apparatus for the same purpose;

Figs. 3 and 4 are views in plan and side elevation, respectively, of one of the new elements in the form of a shingle;

Figs. 5 and 6 are views of the thin and butt ends, respectively, of the new element;

Figs. 7 and 8 are plan and side views, respectively, of a modified form of the element;

Fig. 9 is a detail of the apparatus;

Fig. 10 is a view in side elevation of a part of a modified form of the apparatus;

Fig. 11 is a sectional view of a new element;

Fig. 12 is a sectional view illustrating the manner in which the felt is impregnated;

Fig. 13 is a sectional development view of a part of the shaping apparatus;

Fig. 14 is a sectional view of a part of the apparatus shown in Fig. 13; and

Figs. 15 and 16 are sectional views on the lines 15-15 and 16-16, respectively, of Fig. 13.

In these drawings, the element 20 is illustrated in Figs. 3-6, inclusive, in a form appropriate for use as a shingle. This element is rectangular but its width may lessen toward the thick or butt end 21. The element also tapers in thickness from the rear edge 23 which is the end normally concealed toward the butt or exposed end 21. In a modified form shown in Figs. 7 and 8, the element is of substantially uniform width and thickness from the rear end forward to an imaginary transverse line defining the normal exposure, forward of which the element increases in thickness as indicated at 24, and may decrease in width. The elements are placed on the roof in the usual courses and each element lies with its side edges at the rear end in contact with the side edges of an adjacent element.

Each element comprises a mastic core or base 25 (Figs. 11, 12) which is made up of a mixture of ingredients previously mentioned. The mastic illustrated by way of example preferably includes particles of grit 26, termed a mineral aggregate, fibrous material, and a binder or vehicle, preferably asphalt of a suitable melting point. This mastic forms the core or body of the element, and covering each face and also preferably the end and side edges is a jacket of felted fibres 27 firmly adherent to the core and provided with a coating 28 of asphalt or the like, in which are partially submerged or embedded particles 29 constituting a wear surface. Crushed slate is an example of the granular material frequently used for such a surface, and this may also be used for the aggregate in the mastic, though there are other mineral materials equally suitable and somewhat cheaper such as crushed rock, or sand.

The jacket 27 is preferably made in two pieces, the edges of which may meet without substantial overlap in the median plane of the element. By making the jacket in two pieces, the edges of which meet without substantial overlap, it is possible to produce these elements by a continuous process using certain rotary elements which perform operations without interrupting the progress of the materials, and at the same time apply the jacket so that it covers both faces and all edges of the core and completely encloses it.

The jacket material employed may be of different materials, such as paper of relatively heavy weight, but I prefer to use a light felt produced of rags and similar materials on a paper machine, such felt consisting of felted fibres which provide a porous and ab-

sorbent layer. The felt used however is not comparable in thickness or weight with felts used for standard roofing purposes, but is quite thin, and may vary in weight from 10 to 5 26 pounds to the unit of 480 square feet, while standard roofing felt varies in weight from 20 to 60 pounds for the same unit. The jacket felt is thus very thin and porous, readily shaped and easily impregnated.

10 The new element is made by a process which may be said to involve the application of a coating of asphalt and wear material to one face of a web of this thin felt, the asphalt being applied at a temperature and in 5 amounts such that the asphalt is fluent enough to enter the pores of the felt to a substantial depth. After the wear surface has been applied over this coating, a layer of mastic containing asphalt of the same melt 0 point as that used in the coating is applied on the opposite face of the felt to form a layer of considerable thickness. The mastic is applied at a temperature such that the asphalt therein is relatively fluent and enters 5 the pores of the felt to a depth such that it completes the impregnation thereof, and unites with the asphalt from the coating so that the felt coated on both sides may be described as made up of a mastic body with an 0 asphalt coating carrying granular wear material with a thin layer of felted fibres interposed between the mass of mastic and the coating layer. Following the application of the mastic, the felt is completely impregnated and saturated and firmly bound thereto.

To complete the element, two webs of felt treated as above described are brought into juxtaposition with the mastic layers in contact, then compression is applied to unite the mastic bodies into a single core and to shape the core and jacket, and simultaneously with the shaping operation, the felt webs are severed around the outlines of the formed core to complete the product. In the shaping operation, the jacket sheets are forced into contact at the edges of the shaped core, and severed along the line of contact. This produces a completely jacketed core, without substantial overlap of the jackets, and permits the shaping and severing operations to be carried on by rotary molding and cutting rolls, which produce a completely enclosed core.

This process may be carried on with various forms of apparatus, that shown in Figs. 1A and 1B being convenient and inexpensive. In these figures there are illustrated the two webs of jacket material 30 and 31, mounted on suitable supports so that the webs may be drawn from them without difficulty. Each web 32, 33 passes from its roll through a pair of rolls 34, 35, each roll 34 being provided with a multiplicity of fine spikes, while the corresponding roll 35 has a more or less yielding surface of rubber, leather or wood. The felt passing between these rolls is punctured

at a multiplicity of points and each spike 36 (Fig. 9) is so shaped that as it passes through the felt, it roughens the surface beyond which the spike projects. The rolls 34, 35 are so placed that the face of the felt so roughened is the face to which the mastic is applied. The projecting or roughened parts of the felt then enter the mastic layer and increase the strength of the bond between the mastic and felt. Also the openings in the 70 felt assist in the saturation of the felt and permit solid tongues 28' of asphalt to extend directly therethrough to meet and unite with the asphalt coating layer.

Beyond the perforating devices, the two webs of felt are brought together and pass around a guide roll 37 forming part of a coating mechanism generally designated 38. Standard apparatus well known in the art may be used for this purpose. As illustrated diagrammatically, the two webs of felt, face to face, are led through a vat 39 of coating material beneath a guide roll 40, and a coating material applied to the outer faces and edges. From the vat, the webs pass through rolls 41, which remove excess coating material. The coating material which is preferably asphalt of a melt point sufficient to withstand solar heat is maintained at a suitable temperature in the vat, so that the asphalt will flow readily 95 and thus enter the pores of the felt to a substantial depth.

From the coater the webs pass to mechanism generally designated 42, for applying wear material to the coatings. The details of such mechanism are well known, though these details have here been modified and utilized in a novel way so that surfacing material is applied to opposite faces of the double web. The two webs pass beneath a hopper 43 beneath which is a distributing roll 44, and a layer of the surface grit is spread evenly over the upper surface of the web 33, this grit being partially submerged or embedded in the coating by the roll 45 under which the webs pass. This roll may be hollow and water-cooled so that it gives the coating an initial set at the same time the grit is embedded. The webs now pass around a guide roll 46, so that the web 32 is uppermost and grit is applied to it by the distributing roll 47 receiving grit from the hopper 48, similar to the roll 45, which embeds the grit and sets the coating. The webs then pass to the mechanism for applying the mastic.

This mechanism generally designated 50 includes a pair of rolls 51, 51 placed with their surfaces close together, and the webs 32, 33 pass upwardly between these rolls and are then separated. A supply of the mastic 52 is maintained in the bight of the rolls and kept in place by suitable end plates, not shown. As the webs separate and pass one around each roll 51, the uncoated faces of the webs come in contact with the relatively flu- 130

ent mastic and pick up a layer thereof. Placed to one side and above each roll 57, is a roll 53, 53' journaled in bearings which are adjustable with respect to the bearings 5 for the rolls 51 so that the distance between the surfaces of roll 51 and roll 53, 53' may be varied. Each web is led around the surface of a roll 51, picking up a coating of mastic, then between the roll 51 and its associated 10 roll 53 or 53'. The distance between the surface of roll 51 and roll 53, for example, determines the thickness of the layer of mastic carried off by the web 32, excess mastic being returned to the supply 52. The web 33 passes 15 over its roll 51, then between that roll and roll 53', whereby the thickness of the mastic layer is determined, then around that roll to an upper guide roll 54.

The various rolls 51, 53, 53' and 54 are 20 hollow and arranged so that they may be heated or cooled as may be necessary, and the supply of mastic 52 is kept at a temperature such that the asphaltic ingredient is sufficiently fluent so that it will penetrate the 25 roughened surface of the felt and complete the saturation thereof. Also such of these and other rolls in the apparatus as may be necessary, are driven to cause the felt to advance from its supply through the machine. 30 As the coating asphalt and that in the mastic are preferably the same, they unite in the felt so that there is a substantially continuous asphaltic mass extending through the felted fibres from one face to the other.

35 From the mastic applying mechanism, the two webs of felt are moved to cooling devices, taking the form of rolls 55, around which the two webs are led in a tortuous path. These rolls may be water-cooled so that the coating 40 and the mastic will set partially. These rolls are used to the number desired or necessary to put the coated webs in suitable condition to be combined into building products.

The mechanism used for this purpose is 45 similar to that set forth and described in my co-pending application, Serial No. 139,-612, filed October 5, 1926. That mechanism includes a pair of rotary drums 56, having mold cavities 57 in their surfaces. The webs 50 33, 33 are brought together and pass between the rolls with their mastic layers in contact. The rolls are so shaped that they exert a pressure which consolidates the two mastic layers into a single core of final form, and 55 the jacket webs conform to the shape of this core. Around their edges the mold cavities 57 have sharp edges which pinch the webs and sever them, so that the molding rolls not only form the single elements but cut the webs 60 around the outlines of each element. The drums 56 thus rotate continuously and uniformly and produce finished elements 58 without interruption to the movement of the webs. Each element includes a body or core 5 of mastic, which is completely encased in a

jacket, and by reason of the choice of a two piece jacket, the edges of which meet in a plane without substantial overlap, the rotary forming operation is possible, resulting in a high output rate at low cost. 7

In Fig. 2, there is illustrated a somewhat more compact form of the apparatus. Here the coated webs 32, 33 pass beneath apparatus 59 for applying grit to the upper web 33, then to apparatus 60 for applying grit to the 7 under surface. The grit is embedded in each coating by the passage of the webs between rolls 51 after which the webs are separated and receive the coating of mastic from supply 52. The coated webs now pass directly to the 8 molding drums 56, and the web 32 is guided thereto by roll 53, while web 33 passes around roll 53', guide roll 54 and a floating roll 61 to the drums. The action of the drums may cause mastic to collect in their bight at 62 if excess above that required is carried by the webs. The roll 61 is therefore mounted to float and if mastic collects at 62 in too great amount, it will lift the roll 61 and be carried with roll 53 back to the supply 52. 9

In Fig. 10, there is illustrated in side elevation a modified form of the apparatus, involving the use of two groups of rolls 63 and 64, arranged three high. Each group of rolls is supplied with mastic in any convenient 9 manner, for instance, by placing a container for mastic adjacent each group, one side of each container being defined by the rolls. For this purpose, a pair of downwardly diverging partitions 65 may be used as indicated 1 provided with end plates not shown, and holding quantities of mastic 66 in contact with the surfaces of the two lower rolls of each group.

The web 33 is laid between the two upper 1 rolls of the group 63. The middle roll 67 of this group is spaced from the lower roll and is driven at a higher speed than the top and bottom rolls. The roll 67 picks up a layer 1 of mastic from the supply 66 and carries this layer around in contact with the web 33, spreading the mastic on that web as the roll revolves. The amount of mastic so applied will depend upon the spacing of the middle roll from the top roll and bottom roll. The 1 rolls are journaled in bearings capable of adjustment, so that the thickness of the mastic layer applied to the web can be varied as desired. The coated web passes around the top roll of the group 63 and then around a roll 68 1 and from there is led directly to the forming rolls 56, or it may pass around cooling rolls 55 as desired.

The web 32 passes around a guide roll 69 and then upwardly between the middle roll 1 and the top roll of the group 64. The rolls of this group are arranged in the same manner and perform the same function as the rolls in the group 63, and, from the top roll of this group, the coated web passes either directly 1

to the forming rolls 56, or to cooling rolls 55. It will be noted that mastic is applied to the under surface of the web 33 and to the upper surface of the web 32 by the action of the rolls 67.

It will be seen that the new product can be produced rapidly according to the process described, and the apparatus required is of simple construction and low cost. Apparatus such as that illustrated in Figs. 1A and 1B will occupy floor space not greatly in excess of 60 feet long and of width not much greater than the units to be produced, whereas standard roofing equipment of the type now generally used is over 100 feet long, and includes numerous expensive parts. Since the present product utilizes unsaturated felt, and the felt is saturated as an incident to other operations, the usual saturating equipment is dispensed with, thus reducing the cost and saving space.

While the new product has been illustrated in the form of a single shingle, it may be produced in the form of strip shingles by using molding drums of appropriate form as illustrated in my co-pending application above referred to. It may also be produced without difficulty in numerous other forms for special purposes.

In Fig. 12, I have illustrated a part of the new element in section and on an enlarged scale. The felt jacket 27 is shown as lying between the mastic 25 on one side and the coating layer 28 on the other and due to the porosity of the felt and its perforation, the asphalt in mastic and coating has united so that the felt is completely impregnated and the core and coating form an integral unit. This effect is increased by the tongues 28' of asphalt which extend through the perforations between the coating and core. Accordingly, the new element in final form includes a core, a jacket completely encasing the core, and a water-proof coating with wear material on the jacket and this product has been produced without starting with a saturated felt and without performing special saturating steps.

The present invention affords numerous advantages over the products, processes, and apparatus heretofore used, among which are the following:

By using unsaturated felt the cost of the final product is cut down and this reduction in cost is an important one, since the felt employed is thin and of light weight. The production cost is also reduced since the material is converted from unsaturated felt to finished shingles in what amounts to a single continuous operation, there being no interruption in the travel of the felt through the apparatus. In the new process, the felt and mastic are at practically the same temperature when acted on by the forming and shaping rolls and since the felt is warm it

may be appropriately shaped by these rolls without injury to the felt and without cracking the sealing coating in which the wear material is embedded. This wear material is also firmly affixed to the felt since it passes through two sets of rolls, which act upon it and embed it in the sealing coating. The application of the mastic to the felt itself in a layer of regulated thickness insures a uniform supply of mastic to the forming rolls where the core is shaped to final form, and the mastic at the time it reaches these forming rolls has been subjected to a partial compression to eliminate voids so that the final pressing operation results in products of the highest grade. Also, by reason of the use of unsaturated felt, on one face of which mastic is applied, the binder in the mastic is forced into the fibres of the felt and unites with the sealing coating, both the mastic and sealing coating being warm at the time of the final forming operation, and this prevents any separation or delamination of the felt from the core.

The new product is relatively cheap and it may be made in shingles and building products of any shape and form. Shingles made by the new procedure are particularly desirable since they may have the thick butt, so desirable in roofing products, and not obtained with the ordinary commercial roofing. The thickness of the butt does not increase the cost to any substantial extent, since the body of the new shingle is made of a relatively inexpensive mastic and the amount of felt or jacketing material used does not vary substantially whether the products are thick or thin.

While I have described the method of utilizing the unsaturated felt in a product in which the core is completely encased by the jacket, it will be apparent that the same method may also be used to advantage in the production of jacketed elements of other types such as those shown in my Patent No. 1,585,692, issued May 25, 1926.

I claim:

1. A tapered shingle which comprises a core of intermingled asphaltic material and fibrous material, this core having substantial rigidity, a layer of thin felt on each face of the core, and a sealing coating of asphalt over the felt layers, said coating impregnating the felt and extending through it to the faces of the core to which it is united.

2. A tapered shingle which comprises a core of asphalt and an aggregate, this core having substantial rigidity and constituting the main body of the shingle, layers of thin felt one covering each face of the shingle and said layers meeting along at least a pair of opposite edges of the core, and a sealing coating of asphalt over the felt layers and impregnating the felt, said coating extending

ing through the felt to the faces of the core and adhering thereto.

3. A tapered shingle which comprises a core of intermingled asphaltic material and fibrous material, the said core having substantial rigidity, a thin perforated layer of felt on each face of the core, and a sealing coating of asphalt over the felt layers, the said coating impregnating the felt and extending through the perforations therein to the faces of the core to which it is united.

4. A tapered shingle which comprises a core of asphalt and an aggregate, the said core having substantial rigidity and constituting the main body of the shingle, thin, uniformly perforated layers of felt, one covering each face of the shingle and said layers meeting along at least a pair of opposite edges of the core, and a sealing coating of asphalt over each of the felt layers and impregnating the felt, the said coating also extending through the perforations in the felt to the faces of the core and adhering thereto.

5. A tapered shingle which comprises a core of intermingled asphaltic material and fibrous material, the said core having substantial rigidity, a thin, perforated layer of felt on each face of the core, the core and the felt layers being intimately and permanently bonded together by wiping the core into the felt under pressure, and a sealing coating of fluid asphalt impregnating the felt and extending through the perforations therein to the adjacent faces of the core, thereby intimately bonding the said asphalt to the core through the respective layers of felt.

In testimony whereof I affix my signature.
THOMAS ROBINSON.
